DESIGN FOR A COMBINED BRIDGE AND BRACE FOR AN OPHTHALMIC MOUNT- ING

Samuel E. Bouchard, Rochester, N. Y.

Application December 11, 1936, Serial No. 66,490

Term of patent 14 years

To all whom it may concern:

Be it known that I, Samuel E. Bouchard, a citizen of the United States and a resident of Rochester, county of Monroe, and State of New York, have invented a new, original, and ornamental Design for a Combined Bridge and Brace for an Ophthalmic Mounting, of which the following is a specification, reference being had to the accompanying drawing, forming a part thereof.

Fig. 1 is a front view of a combined bridge and

brace for an ophthalmic mounting showing my new design.

Fig. 2 is a top plan view of same.

Fig. 3 is an enlarged view taken on line 3—3 of Fig. 1.

I claim:

The ornamental design for a combined bridge and brace for an ophthalmic mounting substantially as shown.

SAMUEL E. BOUCHARD.
